CLAIM

The ornamental design for a handheld medication dispensing device, as shown and described.

DESCRIPTION

FIG. 1 is a top-rear, isometric-view of a handheld medication dispensing device;

FIG. 2 is a bottom-front, isometric-view of the handheld medication dispensing device;

FIG. 3 is a rear-view of the handheld medication dispensing device;

FIG. 4 is a left, side-view of the handheld medication dispensing device;

FIG. 5 is a front-view of the handheld medication dispensing device;

FIG. 6 is a right, side-view of the handheld medication dispensing device;

FIG. 7 is a top-view of the handheld medication dispensing device; and,

FIG. 8 is a bottom-view of the handheld medication dispensing device.

1 Claim, 8 Drawing Sheets
